EXEMPLARY CLAIM

1. A compound of the formula:

wherein the expression inside the outer brackets represents a first ion and Z represents a second ion of opposite charge from the first ion, and

A is selected from the class consisting of fluorine and difluoramino groups,

E is selected from the class consisting of fluorine, difluoramino, perfluoroalkyl, difluoramino-substituted perfluoroalkyl, difluoramino-substituted perfluoroalkylfluoramino and

groups,

D is selected from the class consisting of $-NF_2$, $-NFH$ and $=NF$,

Y is selected from the class consisting of $-O-$, $-N=CH-$, $-O-N=CH-$,

and $-NX-$,

X is selected from the class consisting of hydrogen and alkyl groups containing not more than six carbon atoms,

R is selected from the class consisting of mono-, di- and tri- covalent ionic charge bearing groups, *a* and *b* each have values from 1 to 3,

m and *n* are the ionic charges of the individual first and second ions and have integer values from -3 to +3,

p is the covalence of R,

r is the covalence of E and

q is 0-1;

provided that *ma* equals $-nb$,

that when *r* is 2, *p* is 1 and

that when D is $=NF$, *q* is 0.

FLUORINATED OXIDANT COMPOUNDS CONTAINING A FLUORAMINO GROUP

This invention relates to fluorinated compounds and more particularly to certain ionic compounds containing fluorinated oxidant groups in either or both ions.

Fluorinated oxidants have been known heretofore, those of high oxidizing power being of use in propellants and explosives and those of lower oxidizing power being of use as bleaches. Previously known fluorinated oxidants of high oxidizing power have generally been relatively volatile, hydrophobic and somewhat miscible with polymeric binders commonly used in composite propellants, e.g. hydrocarbon, fluorocarbon and cellulosic binders. These properties have often been disadvantageous. In solid propellants, for example, essentially non-volatile constituents are desired for ease and safety of fabrication and storage and dependability of performance on firing. Further, any miscibility of the oxidant with the polymeric binder in a composite propellant composition often tends to weaken the grain physically and/or increase the shock sensitivity thereof. Thus, fluorinated oxidants of sufficiently high oxidizing power to be of value in such propellants have been, at best, difficult to use. Further, the volatility and hydrophobicity (i.e. water insolubility) of the fluorinated oxidants have often been disadvantageous with respect to their use as bleaches.

It is an object of the present invention to provide a novel and useful class of fluorinated oxidants which are normally solids or low-volatility liquids. It is another object of the invention to provide non-volatile solid ionic compounds containing fluorine bonded to nitrogen. It is another object of the invention to provide useful salts which contain oxidizing fluorine-nitrogen groups in either the anion or the cation or in both. It is another object of the invention to provide fluorinated oxidizing agents which have a high degree of compatibility with (i.e. can be easily used with) complementary constituents of high performance solid propellant compositions such as polymeric binders. It is another object of the invention to provide fluorinated oxidizing agents of low volatility which have very low solubilities in polymeric binders. It is another object of the invention to provide low volatility, water soluble ionic compounds useful as bleaches. Other objects of the invention will become evident from the following specification.

In accord with the above and other objects of the invention, it has been found possible to prepare stable, essentially non-volatile (i.e. having a volatility of less than 1 mm. of mercury at 25°C.) ionic oxidant salts of the formula:

wherein the expression inside the outer brackets represents a first ion and Z represents a second ion of opposite charge from the first ion, and

A is selected from the class consisting of fluorine and difluoramino groups.

E is selected from the class consisting of fluorine, difluoramino, perfluoroalkyl, difluoramino substituted perfluoroalkyl, difluoramino substituted perfluoroalkylfluoramino and N^{F} groups,

D is selected from the class consisting of $-\text{NF}_2$,

—NFH and =NF,

Y is selected from the class consisting of $-\text{O}-$,
 $-\text{N}=\text{CH}-$,

X is selected from the class consisting of hydrogen and alkyl groups containing not more than six carbon atoms,

R is selected from the class consisting of mono-, di- and tri-covalent ionic charge-bearing groups, *a* and *b* each have values from 1 to 3, *m* and *n* are the ionic charges of individual first and second ions and have integer values from -3 to +3 (not zero)

n is the covalence of R

β is the covalence of R,
 γ is the covalence of E and

γ is the C

q is 0-1,
provided that ma equals $-nb$ and

provided that m equals $-nb$ and provided that when r is 2, n is 1 and

provided that when γ is 2, p is 1 and provided that when D is $\equiv$ NE, q is 0

The carbon atom shown in the foregoing general formula is bonded directly to a nitrogen or oxygen atom in Y. E in that formula preferably contains not more than five carbon atoms.

A preferred class of compounds of the invention are those in which R is TV wherein T is a single covalent bond, an alkylene group containing 1 to 18 carbon atoms, an arylene group containing 6 to 12 carbon atoms or an aralkylene group containing 7 to 14 carbon atoms and V is an ionic group and includes

wherein each R^a is hydrogen or alkyl containing up to six carbon atoms and m is 0-6, provided that when T is a single covalent bond, then Y and V taken together can only be

The ionic nature of the salts of the invention can be conveniently demonstrated by noting the significant increase in the conductivity of acetonitrile when such salt is added thereto. In general, in the compounds of the invention the algebraic sum of the pK_b of the conjugate base of the cation and the pK_a of the conjugate acid of the anion is less than 13. Thus, as will be shown hereinafter, salts of the invention can be prepared by the reaction of a strong acid with a weak base and vice versa.

The ionic compounds of the invention which are particularly useful as explosives, monopropellants and solid rocket fuel ingredients are those of which 50 to 70 per cent of the total weight is made up of fluorine bonded to nitrogen and of oxygen. It is this group of compounds which have the high oxidizing power required for propellant compositions yet which have the desirable physical properties and compatibility with other propellant constituents which are required for this application.

Referring to Z in the foregoing general formula, when the compounds of the invention are to be used as explosives or propellants a preferred class of anions includes those which contain significant amounts of energetically bound oxygen or fluorine such as ClO_4^- , NO_3^- , ClO_3^- , BrO_3^- , IO_3^- , and anions which contain nitrogen bonded to fluorine and a preferred list of cations includes Li^+ , Na^+ , K^+ , Mg^{++} , Be^{++} , NH_4^+ , NH_2NH_3^+ , and cations which contain nitrogen bonded

to fluorine. Thus salts in which the ion Z falls within the definition of the first ion within the outer brackets in the foregoing general formula are also included in the invention.

5 A particularly preferred class of compounds of the invention for explosives and propellant uses are those in which the N-F bearing group is in the cation and the anion is perchlorate. Since the precursor perchloric acid is very strong (having a pK_a of -8), it forms salts 10 with a wide variety of bases, including very weak bases. In addition, the perchlorate anion itself contributes materially to the oxidizing power of the compound. The calculated specific impulses of several of these compounds are given in the following tables.

15

Monopropellants

Structure	Isp	Chamber Temperature °C.
$\text{ClO}_4^-\text{H}_3^+\text{NOC}(\text{NF}_2)_3$	232.5	2757

20 $\text{ClO}_4^-\text{H}_3^+\text{N}^+\text{CH}_2\text{CH}_2\text{OC}(\text{NF}_2)_3$	296.8	3935

Solid Propellants

Composition (weight %)	I _{sp}	Chamber Temp. °C.
25 54 $\text{ClO}_4^-\text{H}_3^+\text{OC}(\text{NF}_2)_3 + 16 \text{ Li} + 30 \text{ C}_3\text{F}_7\text{NO}(1)$	291.4	3975
54.3 $\text{ClO}_4^-\text{H}_3^+\text{CH}_2\text{OC}(\text{NF}_2)_3 + 15.7 \text{ Li} + 30 \text{ C}_3\text{F}_7\text{NO}$	284.7	3788
54.6 $\text{ClO}_4^-\text{H}_3^+\text{N}^+\text{CH}_2\text{CH}_2\text{OC}(\text{NF}_2)_3 + 15.4 \text{ Li} + 30 \text{ C}_3\text{F}_7\text{NO}$	279.8	3532
(1) $\text{C}_3\text{F}_7\text{NO}$ is a copolymer of tetrafluoroethylene and nitrosotri-fluoromethane which is used as the binder.		

Compounds of the invention can be prepared by adding a compound containing at least two reactive functions in which at least one function contains active hydrogen carried by a nitrogen or oxygen atom (sometimes referred to herein as the addend compound) across a

40 45 50 55 60 65 70 75 80 85 90 95 100 double bond in a fluorinated oxidant compound of the formula:

wherein A and E are as previously defined. Illustrative compounds of this type are as follows:

These fluorimino containing compounds can be prepared by two general routes. Those compounds which contain perfluoroalkyl groups of more than one carbon atom are prepared by reductive defluorination of the

corresponding saturated difluoramino perfluoroalkyl compounds (which are prepared by methods such as those described by Lovelace et al., "Aliphatic Fluorine Compounds", pages 20-23 (1936), Reinhold Publishing Co., New York) with suitable reducing agents such as ferrocene. Direct fluorination, as by the use of the Simons fluorination cell, can also be used to prepare the starting materials for reductive defluorination. The other fluorimino compounds, all of which contain an alternating nitrogen-carbon skeletal structure, are prepared by the direct fluorination of starting materials such as ammeline, guanidine, biguanide and melamine or the hydrofluoride salts thereof. The fluorimino compounds are isolated and purified by gas-liquid chromatography in which high boiling fluorocarbon compounds are used as the stationary phase. Methods for the production of these compounds are disclosed in the co-pending applications of our co-workers, Ser. Nos. 99,632, filed Mar. 30, 1961; now U.S. Pat. No. 3,461,162.; 19,111, filed Mar. 31, 1960 now U.S. Pat. No. 3,354,216.; and Ser. No. 19,112, filed Mar. 31, 1960, now abandoned.

Broadly the addend compounds which are useful in preparing the compounds of the invention include those containing hydroxyl or primary or secondary amino groups which can add to fluoramine functions and also groups which are ionic in nature such as salts of very strong acids with amines, amidines and hydrazides or groups which can be converted to ionic groups such as carboxylic acids, carboxylic esters, carboxylic amides, nitriles, sulfonic acids, sulfonic acid esters, sulfonic acid amides, oximes, hydroperoxides, tertiary amines and monosubstituted acetylenes.

The reaction in which the addend compound contains a group which is convertible into an ionic group can be represented as follows: 35

wherein A, E, Y, p and r are as previously defined as Q is a group which does not enter into this reaction and which is convertible into an ion bearing group (R) having m (i.e. -3, -2, -1, +1, +2 or +3) ionic charges. 45

When the addend compound contains an ionic group, the reaction can be represented as follows:

wherein the notation is as previously set out.

When the $-\text{OH}$ or $-\text{NH}-$ groups in the addend compound are very weakly nucleophilic the addition reaction to fluorimino compounds can often be accelerated by the use of basic catalysts such as triethylamine, urea, etc. 65

The —NFH adduct products of either of the foregoing reactions are convertible by fluorination into the corresponding —NF₂ adducts or by elimination of HF or HNF₂ by the action of heat or base into the unsaturated =NF compounds, e.g.:

The adducts of the type

can be converted to compounds of the invention by transforming the unreacted function Q to the ion bearing group R using various methods, the method which is used for a particular addend depending largely upon the nature of the addend used in preparing it. Thus:

A. When the unreacted function is a carboxylic acid group, the intermediate adduct can be neutralized with a base to form the salt. Addends used in preparing such intermediate adducts are:

B. When the unreacted function is a potentially acidic group, the intermediate adduct can be hydrolyzed to the acid and neutralized to obtain the salt or saponified to obtain it directly. Suitable addends include:

$\text{HOCH}_2\text{CONH}_2$ and $\text{HOCH}_2\text{CH}_2\text{SO}_2\text{NH}_2$, etc.
where x is 1 to 18.

C. When the unreacted function in the intermediate adduct is a potentially basic group, it can be converted to a base and the product neutralized with an acid to form the salt or it can be converted directly to a salt by hydrolysis. Where the potentially basic group is an ester, it can be converted to a hydrazide using hydrazine and where it is a nitrile, it can be converted to a hydrazidine or amidine using hydrazine and ammonia and these then treated with acids to form salts. Suitable addends include:

and $\text{HO}(\text{CH}_2)_x\text{C} \equiv \text{N}$ wherein x is as previously defined.

D. When the functions of the addend are identical (or closely similar) and both contain active hydrogen, the intermediate adduct is obtained by reacting equimolar quantities of the fluorinated oxidant and the addend compound. This intermediate adduct or the product of its fluorination is then reacted with an appropriate strong base to form the salt. Suitable addends are:

E. When the unreacted function is weakly acid, the adduct can be reacted with a strong base (e.g. LiC_4H_9) to form the salt. Suitable addends are: $\text{HO}(\text{CH}_2)_x\text{C}=\text{CH}$, $\text{HOCH}_2\text{CH}_2\text{OH}$ and H_2O_2 .

F. In certain cases one salt of the invention can be prepared from another by metathesis, e.g. the ClO_4^- salt can be prepared from the chloride salt by reaction with AgClO_4 in ethanol and the B_3H_8 salt can be prepared from the chloride salt and NaB_3H_8 in a suitable solvent. Similarly the chloride ion in the chloride salt can be replaced by many other ions by treatment with a suitably prepared ion exchange resin.

The properties of the fluorinated oxidants must of course be taken into consideration and overheating of sensitive compounds must be avoided. Many of the compounds of the invention have a very high N-F content and may explode with high energy release. Caution must be exercised during the preparation and manipulation of these products such as performing operations behind suitable shields and wearing protective jackets, gloves and ear plugs to prevent personal injury in the event of explosions. The occasional explosion of perfluoroguanidine when frozen to -196°C . during vacuum transfers is largely avoided by transferring in *vacuo* at temperatures above the melting point of perfluoroguanidine, e.g. -111°C ., using a fluorotrichloromethane slush bath as the cooling medium.

Except for the foregoing, however, the reactions of types A.-F. above can be carried out by methods generally known to those skilled in the art.

Once the compounds of the invention have been prepared, a number of purification techniques can be

used. Their high stability toward air and moisture permits the use of the conventional techniques of recrystallization, solvent extraction, ion-exchange and liquid column chromatography. The latter technique is of great value when coupled with thin layer chromatography techniques which permit the choice of proper supports and solvents using very small quantities. In some cases, sublimation is of value in the purification of these compounds.

- 10 The compounds of the invention are liquids or solids having strong oxidizing power. They are useful as explosives and for incorporation into propellants as the oxidant component and for other applications in which their oxidizing power can be utilized, as, for example, 15 as bleaching agents and the like.

The following examples will more specifically illustrate the preparation of the compounds of the invention. All parts are by weight unless otherwise specified.

EXAMPLE 1

Preparation of

by the following reactions:

To a glass ampoule charged with 42 mg. of the methyl ester of glyoximic acid and 0.1 ml. of dry acetonitrile is added 57 mg. of perfluoroguanidine at -196°C . The ampoule is sealed and allowed to warm gradually to 25°C . At the end of 12 hr. at 25°C . the solvent is removed under vacuum and to the residue (which is nearly pure $\text{CH}_3\text{OCOCH}=\text{NOC}(\text{NF}_2)_3\text{NFH}$ as shown by F n.m.r. absorptions at -22.6δ due to NF_2 and at $+137.6 \delta$ due to NFH) is added about one ml. of trifluoroethanol. The adduct is fluorinated by circulating through this solution, in a closed dry glass system, 0.50 mmole of fluorine in about 1500 ml. of nitrogen gas at atmospheric pressure. The fluorination is continued for 3 hr. as the temperature is raised from -23°C . to 20°C . The fluorinated adduct $\text{CH}_3\text{OCOCH}=\text{NOC}(\text{NF}_2)_3$, F n.m.r. -23.5δ , is thus obtained. After removal of solvent the ester moiety is hydrolyzed with 8 mg. of lithium hydroxide in about 2 ml. of 50 percent aqueous acetonitrile using moderate heating over a period of 30 min. Evaporation of the solvent yields the lithium salt which may be purified by recrystallization, solvent extraction, or other suitable means. Alternatively, the ester may be hydrolyzed by gently heating the fluorinated adduct in 2 ml. of 0.5 M hydrochloric

acid for about 30 min. Neutralization of this solution with aqueous lithium hydroxide and subsequent evaporation of solvent yields the crude lithium salt.

EXAMPLE 2

Preparation of

by the following reactions.

To 270 mg. of the fluorinated adduct described in Example 1 is added 34 mg. of 95 percent hydrazine (a solvent, such as acetonitrile may be added). The temperature of the resulting reaction is maintained below 25°C. by cooling. At the end of one hr. the solvent, if any, is removed under vacuum and the residue, $\text{H}_2\text{NNHCOCH}=\text{NOC}(\text{NF}_2)_3$, is dissolved in one ml. of water containing 37 mg. of hydrogen chloride at 25°C. Water is removed from the mixture after 30 min. The resulting hydrogen chloride salt may be purified by recrystallization, solvent extraction or other suitable means.

Alternatively, the hydrochloride salt may be prepared by dissolving 300 mg. of the hydrazide described in the preceding paragraph in one ml. of the dimethyl ether of ethylene glycol. Dry hydrogen chloride gas is bubbled through this solution until precipitation of the hydrogen chloride salt is complete. The salt is filtered off and purified by the techniques described.

EXAMPLE 3

Preparation of

by the following reactions:

To 270 mg. of the fluorinated adduct described in Example 1 is added 34 mg. of 95 percent hydrazine (a solvent such as dry acetonitrile may be added). The temperature of the resulting reaction is maintained below 30°C. by cooling if needed. At the end of one hr. the solvent, if any, is removed under vacuum and the residue is dissolved in 1 ml. of water containing 100 mg. of perchloric acid at 25°C. Water is removed from the mixture after 30 min. under vacuum. The resulting perchlorate salt of the hydrazide may be purified by recrystallization, solvent extraction or other suitable means.

An alternative method of preparation is as follows: To 203 mg. of the perchlorate salt of the hydrazide of glyoxime acid in about 1 ml. of dry acetonitrile is added 149 mg. of perfluoroguanidine at -196°C. The ampoule is sealed and allowed to warm gradually to 25°C. After 12 hr. at this temperature the solvent is removed under vacuum and to the residue is added about 1 ml. of trifluoroethanol. The adduct is fluorinated as described in the previous example using 0.63 mmole of fluorine in about 1500 ml. of nitrogen over a period of 3 hr. starting at -23°C., warming gradually to 20°C. After removal of the solvent the resulting solid may be purified by recrystallization, solvent extraction or other suitable means.

The perchlorate salt of the fluorinated adduct is also obtained by dissolving 307 mg. of the hydrochloride salt of Example 2 in 10 ml. of ethanol along with 207 mg. of silver perchlorate. The silver chloride which precipitates is filtered off. Evaporation of the ethanol yields the desired perchlorate salt of the hydrazide which may be purified by recrystallization, solvent extraction, or other suitable means.

EXAMPLE 4

50 Preparation of $\text{Li}^+\text{O}^-\text{N}=\text{CH}-\text{CH}=\text{NOC}(\text{NF}_2)_3$ by the following reactions:

To a glass ampoule charged with excess glyoxime (150 mg.) and about 0.5 ml. of dry acetonitrile is added 60 mg. of perfluoroguanidine at -196°C. The tube is sealed and the reaction mixture is allowed to warm

gradually to 25°C. After 10 days at this temperature the solvent is removed from the unreacted glyoxime and concentrated under vacuum to yield the mono-adduct contaminated with some of the di-adduct. This product is dissolved in about 1 ml. of trifluoroethanol and fluorinated using 0.50 mmole of fluorine in about 1500 ml. of nitrogen using the technique described in Example 1. After fluorination, one ml. of a solution containing 8 mg. of lithium hydroxide in water is added. Removal of the solvents under vacuum yields the lithium salt of the fluorinated adduct. Impurities are removed by recrystallization, solvent extraction, or other suitable means.

EXAMPLE 5

Preparation of

by the following reactions:

To a glass ampoule fitted with a Fischer-Porter Teflon needle valve and charged with 29 mg. of n-butyl glycolate and 0.5 ml. acetonitrile is transferred 30 mg. of perfluoroguanidine at -110°C. The valve is closed and the tube let warm to room temperature. Over a period of about 16 hrs. a high conversion to the adduct $C_4H_9OCOCH_2OC(NF_2)_2NFH$ is obtained as shown by fluorine nuclear magnetic resonance (F n.m.r.) and infrared analyses. The F n.m.r. absorptions are at 21.7 ϕ (doublet due to NF_2) and 140.9 ϕ (double quintuplet due to NFH).

The adduct is fluorinated to yield $C_4H_9OCOCH_2OC(NF_2)_3$ (as shown by a single absorption in F.n.m.r. at about -23δ due to NE_2).

The fluorination is carried out by passing 2 percent fluorine (diluted with nitrogen) at the rate of about 100 cc/min through the adduct solution at -20°C . approximately 1 hour via a stainless steel dip tube placed in the solution.

The fluorinated adduct solution is shaken with about 50 mg. of powdered NaF to remove HF which is produced as a by-product in the fluorination. The mixture is filtered by centrifuged to remove the solid.

The neutral fluorinated adduct solution is heated for 0.5 hr. (at about 60° C.) with 0.5 cc of water containing 4 mg. of lithium hydroxide. Evaporation of the solvent under vacuum yields the lithium salt Li

$\text{O}^+ \text{--COCH}_2\text{OC}(\text{NF}_2)_3$ which may be purified by recrystallization, solvent extraction or other suitable means.

In the glass ampoule described above is placed 16 mg. of recrystallized anhydrous glycolic acid and 0.5 ml. of dry acetonitrile. To this solution is transferred 30 mg. of perfluoroguanidine at -110°C .

Over a period of three days a good conversion to the adduct $\text{HOCOCH}_2\text{OC}(\text{NF}_2)_2\text{NFH}$ is obtained as shown by fluorine nuclear magnetic resonance absorptions at $10\text{ }\phi - 21.7\text{ }\phi$ due to NF_2 and $+140\text{ }\phi$ due to NFH .

The adduct is fluorinated as described above to yield $\text{HOCOCH}_2\text{OC}(\text{NF}_2)_3$. After treatment with NaF , the acetonitrile solution is mixed with 0.5 cc of water containing 4 mg. of lithium hydroxide. The product $\text{LiO}^+\text{COCH}_2\text{OC}(\text{NF}_2)_3$ is isolated as above.

EXAMPLE 6

Preparation of

and its fluorination to form

and the preparation of the latter by the following reactions:

The NaF treated fluorinated adduct solution from Example 5 containing about 60 mg. of $C_4H_9OCOCH_2OC(NF_2)_3$ is reacted with 7 mg. of 95% hydrazine. The temperature is maintained below 30° by cooling if necessary. At the end of about 1 hour, the solvent is removed under vacuum and the crude hydrazide $H_2NNHCOCH_2OC(NF_2)_3$ is dissolved in 0.5 cc. water containing 20 mg. of perchloric acid. Water is removed under vacuum to yield the salt $ClO_4^-N^+NH_3NHCOC(CH_2OC(NF_2)_3)H_3$ which may be purified by recrystallization, solvent extraction or other suitable means.

An alternative method of preparing this salt is as follows: To 95 mg. of the perchlorate salt of 2-hydroxyacetohydrazide, $\text{ClO}_4^- \text{N}^+ \text{H}_3\text{NHCOCH}_2\text{OH}$, in 1 ml. of dry acetonitrile in the apparatus of Example 5 is added 75 mg. of perfluoroguanidine at -110°C . The valve is closed and the reactor let warm to room temperature. After about 1 week the adduct $\text{C10}_4^- \text{N}^+ \text{H}_3\text{NHCOCH}_2\text{OC}(\text{NF}_2)_2\text{NFH}$ is obtained in moderate conversion. The solvent is removed under vacuum and to the residue is added about 1 ml. of trifluoroethanol. The adduct is fluorinated as in example 5 except that the fluorination time is increased to 3 hours. Removal of the solvent under vacuum affords the perchlorate salt $\text{ClO}_4^- \text{N}^+ \text{H}_3\text{NHCOCH}_2\text{OC}(\text{NF}_2)_3$ which may be purified as described above.

EXAMPLE 7

Preparation of $\text{Li}^+\text{O}^-\text{CH}_2\text{CH}_2\text{OC}(\text{NF}_2)_3$ by the following reactions:

The monoadduct of ethylene glycol and perfluoroguanidine is prepared as follows:

One tenth ml. of a dry acetonitrile solution containing $8.85 \text{ mg. } (1.43 \times 10^{-4} \text{ moles})$ of ethylene glycol is transferred in a dry nitrogen atmosphere to a slender cylindrical dry glass vessel of 1.5 ml. capacity which is then connected to a vacuum manifold system. The acetonitrile solution is chilled to -196°C . and $24.4 \text{ mg. } (1.64 \times 10^{-4} \text{ moles})$ of pure perfluoroguanidine are added by distillation, as well as a minute reference amount of tetramethyl silane. The vessel is closed and the solution allowed to warm to room temperature. After 5 days, the proton nuclear magnetic resonance spectrum shows twin weak bands centered at about -1.2τ and 0.1τ and strong complex bands centered at about 5.5τ and 6.2τ in addition to the reference absorptions due to $(\text{CH}_3)_4\text{Si}$ and CH_3CN . Fluorine n.m.r. shows very weak twin absorptions at about -47ϕ and -41ϕ , a single sharp absorption at about -21ϕ and weak doublet absorption at about 140.5ϕ (estimated J about 50 cps). All these data are consistent with the structure:

To 126 mg. of $\text{HOCH}_2\text{CH}_2\text{OC}(\text{NF}_2)_2\text{NFH}$ in a glass reactor is added 2 ml. of trifluoroethanol. This adduct is fluorinated by recirculating nitrogen containing 6% F_2 (a total of 1 mole equivalent F_2) through the above solution at -20° to -10°C . for a period of 7 hours.

The fluorinated adduct thus obtained has the structure $\text{HOCH}_2\text{CH}_2\text{OC}(\text{NF}_2)_3$ as shown by a strong fluorine nuclear magnetic resonance absorption at -23.6ϕ due to NF_2 and there is absence of an absorption at $+140 \phi$ due to NFG .

The trifluoroethanol solution of the fluorinated adduct is treated with NaF to remove any HF , then filtered or centrifuged to remove solid and the filtrate concentrated under vacuum. This residue is taken up in dry benzene (3 ml.) and 3 cc. of hexane containing 38 mg. of n-butyl lithium is added with stirring under anhydrous conditions at 0°C . After 1 hour the lithium salt $\text{Li}^+\text{O}^-\text{CH}_2\text{CH}_2\text{OC}(\text{NF}_2)_3$ is isolated by removing the solvent under vacuum. The salt is purified by recrystallization, solvent extraction or other suitable means. It is stored protected from moisture.

EXAMPLE 8

Preparation of $\text{ClO}_4^-\text{N}^+\text{H}_3\text{CH}_2\text{CH}_2\text{OC}(\text{NF}_2)_2\text{NFH}$ and its fluorination of $\text{ClO}_4^-\text{N}^+\text{H}_3\text{CH}_2\text{OC}(\text{NF}_2)_3$ by the following reactions:

5

- 10 Into a 5 ml. reactor fitted with a Fischer-Porter Teflon valve is added $0.162 \text{ g. } (1 \times 10^{-3} \text{ moles})$ of ethanolamine perchlorate and one milliliter of acetonitrile (0.25% H_2O). After degassing, $0.360 \text{ g. } (2.42 \times 10^{-3} \text{ moles})$ of perfluoroguanidine is condensed into the reactor at -119°C . The mixture is allowed to warm to and remain at room temperature over a 2 week period. After this time, the volatile contents of the reactor are separated by fractional distillation-condensation techniques and $1.26 \times 10^{-3} \text{ moles}$ of perfluoroguanidine is recovered. The semi-solid residue in the reactor is subjected to reduced pressure for 4 hours at room temperature and then dissolved in acetonitrile. A fluorine nuclear magnetic resonance spectrum on this solution shows the major absorption at -22.0ϕ (NF_2) and a doublet at $+141.1 \phi$ (NFH). The only other absorption is at $+149.1 \phi$ and is presumed to be due to BF_4^- . These data indicate that $\text{ClO}_4^-\text{N}^+\text{H}_3\text{CH}_2\text{OC}(\text{NF}_2)_2\text{NFH}$ is present.

To the crude reaction mixture described above which has again been dried in vacuo is added 1.6 ml. of trifluoroethanol. The resulting colorless solid suspension is then cooled to -23°C . and $2 \times 10^{-3} \text{ moles}$ of fluorine (5% by volume in nitrogen) is circulated through the sample over a 6 hour period as it warms from -23° to $+20^\circ\text{C}$.

The colorless trifluoroethanol solvent is withdrawn from the reactor by means of a capillary syringe and placed in a nuclear magnetic resonance tube fitted with a Fischer-Porter valve. Evaporation in vacuo affords 40 0.103 g. of a colorless glass which is divided in half. A 0.051 g. portion of the crude product is pumped on for an additional 22 hours at room temperature to give 45 0.048 g. of a semi-solid which is dissolved in acetonitrile. The F^{19} n.m.r. spectrum exhibits a major band at -24.0ϕ (NF_2) and a less intense band at $+149.1 \phi$ (BF_4^-). Three other very minor absorptions are present at -20.6 , -19.5 and $+74.3 \phi$.

The salt is purified by liquid column chromatography 50 on a silica gel column utilizing the following order of solvents; chloroform, 50:50 chloroform-ethyl acetate, ethyl acetate and ethanol. The product, $\text{ClO}_4^-\text{N}^+\text{H}_3\text{CH}_2\text{CH}_2\text{OC}(\text{NF}_2)_3$, which is obtained by evaporation of the ethyl acetate eluate, is a colorless solid melting with decomposition at about 188° - 193°C .

A sample of $\text{ClO}_4^-\text{N}^+\text{H}_3\text{CH}_2\text{CH}_2\text{OC}(\text{NF}_2)_3$, the preparation of which is described above is dissolved in water. The solution is slowly neutralized with 10% aqueous sodium hydroxide to a pH of 8. The precipitated yellow-colored oil is extracted from the aqueous solution with diethyl ether. The ether extract is dried with CaSO_4 and evaporated to dryness. The free amine product, $\text{NH}_3\text{CH}_2\text{CH}_2\text{OC}(\text{NF}_2)_3$, is purified by liquid column or vapor phase chromatography.

EXAMPLE 9

Preparation of $\text{ClO}_4^-\text{N}^+\text{H}_3\text{CH}_2\text{CH}_2\text{OC}(\text{NF}_2)_3$ and $\text{Cl}^-\text{N}^+\text{H}_3\text{CH}_2\text{OC}(\text{NF}_2)_3$ by the following reactions:

A sample of pure N-hydroxymethylsuccinimide (m.p. 64.5°–66°C.) weighing 0.194 grams (1.5×10^{-3} moles) is placed in a dry 3 ml. ampoule fitted with a Fischer-Porter Teflon valve. Dry acetonitrile (0.8 ml.) is then added to the ampoule followed by 0.373 grams (2.5×10^{-3} moles) of perfluoroguanidine. The reaction mixture turns an amber-color while standing for 4½ days at 25°C. The mixture is evaporated to dryness, subjected to reduced pressure for 25 hours (weight = 0.417 grams 95% yield) and dissolved in 1.5 cc of trifluoroethanol. The F^{19} nuclear magnetic resonance spectrum shows an absorption at -22.0δ characteristic of the NF_2 group and a doublet assigned to the NFH at $+139.6 \delta$.

The solution of the adduct in 1.5 cc. of trifluoroethanol described above is fluorinated with 4×10^{-3} moles of fluorine by the procedure used in Example 8. The fluorination is continued for a total of 16 hours at initial and final temperatures of -23° and $+25^\circ$ C., respectively. The fluorine n.m.r. spectrum suggests an approximately 80% conversion to the tris(difluoramino) derivative by a new NF_2 absorption at -24.3δ consistent with the tris(difluoramino) methyl group and disappearance of the $-NFH$ absorption at 139.6δ .

A sample of the above fluorinated adduct is dissolved in 95% ethanol which contains one molar equivalent of hydrazine hydrate. The mixture is heated at reflux temperature for a short time, cooled, filtered and the filtrate acidified with perchloric acid. The desired amine-perchlorate is obtained by complete removal of the volatiles in vacuum. The salt is purified by recrystallization or liquid column chromatography.

An alternate route to $HClO_4 \cdot NH_2CH_2OC(NF_2)_3$ involves the acid hydrolysis of the aforescribed fluorinated N-hydroxymethylsuccinimide adduct. The adduct is dissolved in a mixture of acetic and hydrochloric acids and heated to 100°C. The hydrochloride salt of the desired product is recovered from the reaction mixture, dried and dissolved in ethanol. A stoichiometric amount of silver perchlorate, dissolved in ethanol,

is added to the solution and the silver chloride precipitate is filtered. Complete evaporation of the ethanol filtrate yields the desired perchlorate salt.

Another route to $HClO_4 \cdot NH_2CH_2OC(NF_2)_3$ is by heating the fluorinated N-hydroxymethylsuccinimide-perfluoroguanidine adduct in aqueous perchloric acid. The perchlorate salt is recovered by complete evaporation of the solution after the succinic acid by-product is removed by filtration. Purification is accomplished by liquid column chromatography or recrystallization.

EXAMPLE 10

Preparation of $HClO_4 \cdot NH_2OC(NF_2)_2NFH$ and its fluorination to $HClO_4 \cdot NH_2OC(NF_2)_3$ and the preparation 15 of the latter by a different process using the following reactions:

20

Hydroxylamine perchlorate is prepared as follows:

Samples of anhydrous silver perchlorate (1.0 gram) and anhydrous hydroxylamine hydrochloride (0.35 gram) are each dissolved in 100 milliliters of 100% ethanol. A potentiometric titration of the two solutions shows that 1.105 ± 0.005 milliliters of the ethanolic hydroxylamine hydrochloride is equivalent to 1.000 milliliters of the silver perchlorate solution.

To a stirred 20.0 milliliter sample of the silver perchlorate solution is rapidly added 22.1 milliliters of the hydroxylamine hydrochloride solution. The precipitated silver chloride is removed by filtration and the clear ethanolic filtrate evaporated to dryness under vacuum. The resulting hydroxylamine perchlorate is a colorless solid melting at 84° – 87° C.

Utilizing the same general procedures as outlined previously, 0.262 g. (1.96×10^{-3} moles) of hydroxylamine perchlorate and 3 cc. of dry acetonitrile are added to a dry 10 cc. ampoule (dry nitrogen atmosphere). The solution is then cooled to -111° C., degassed to less than 0.1 mm of mercury pressure and 0.745 g. (5×10^{-3} moles) of perfluoroguanidine is added by condensation.

The mixture is allowed to warm to and remain at room temperature for about 7–10 days. Agitation is accomplished by means of a magnetic stirring bar which is contained in the ampoule. The solvent and excess perfluoroguanidine are removed from the reactor by vacuum transfer techniques. The F^{19} n.m.r. spectrum of the resultant yellow, non-volatile, semi-solid residue exhibits a peak at about -33δ assigned to the $-NF_2$ group and a poorly resolved doublet in the 110δ region assigned to the NFH .

Fluorination of the adduct is accomplished by dissolving the material in trifluoroethanol, cooling to -23° C. and circulating a dilute stream of fluorine in nitrogen through the solution as it warms to 0°C. Evaporation of the fluorination solvent affords a semi-solid residue of the desired perchlorate salt. Final purification is accomplished by liquid column chromatography, recrystallization or solvent extraction.

Another method of preparation of $\text{ClO}_4^- \text{H}_3\text{N}^+ \text{OC}(\text{NF}_2)_3$ is as follows: equimolar amounts of acetone oxime and perfluoroguanidine are mixed at -111°C . and allowed to warm slowly. The adduct $(\text{CH}_3)_2\text{C}=\text{NOC}(\text{NF}_2)_2\text{NFH}$ is obtained in high yield. This adduct is stirred, cooled to -30°C . and is fluorinated with a stream of 2-3% fluorine in dry nitrogen at a flow rate of about 150 ml per minute. The product $(\text{CH}_3)_2\text{C}=\text{NOC}(\text{NF}_2)_3$ remains in the fluorination flask and is obtained in about 50% yields. Smaller amounts of

are also formed. Alternatively the $-\text{NFH}$ adduct may be fluorinated as a dilute solution in trifluoroethanol by bubbling dilute fluorine (about 5-10%) through the solution at temperatures from -50° to 25°C . The desired products can be isolated by distillation or by vacuum fractionation or by gas chromatography.

A mixture of $(\text{CH}_3)_2\text{C}=\text{NOC}(\text{NF}_2)_3$ prepared as described above, and an equimolar amount of HClO_4 in water in a closed vessel is stirred and heated gently for thirty minutes. The water is removed in vacuo at 25°C . and the desired perchlorate salt, $\text{ClO}_4^- \text{H}_3\text{N}^+ \text{OC}(\text{NF}_2)_3$, is obtained as a semi-solid residue.

EXAMPLE 11

Preparation of $\text{Mg}^{++} (\text{O}_2\text{CCH}_2\text{NCH}_3\text{C}(\text{NF}_2)_3)_2$ by the following reactions:

To a mixture of perfluoroguanidine in dry carbon dioxide free dimethyl ether in closed glass flask at -111°C . is added with stirring a cold solution of $\text{CH}_3\text{NHCH}_2\text{CN}$ in dimethyl ether. The mixture is allowed to warm slowly to -40°C . and the dimethyl ether is removed in vacuo at -40°C .

The product is

complexed with dimethyl ether. The viscous yellow liquid residue is fluorinated at -30°C . with stirring with a 10 mole excess of 3 percent fluorine in dry nitrogen at a flow rate of about 150 cc per minute. The yellow liquid which remains in the flask after fluorination is mainly $(\text{F}_2\text{N})_3\text{CN}(\text{CH}_3)\text{CH}_2\text{CN}$. This nitrile is gently heated with excess dilute aqueous sodium hydroxide until dissolution occurs. The solution is acidified with dilute aqueous hydrochloric acid and the acid $(\text{NF}_2)_3\text{CN}(\text{CH}_3)\text{CH}_2\text{COOH}$, is obtained as a yellow oil. This oil is dissolved in methanol, an equivalent amount of $\text{Mg}(\text{OCH}_3)_2$ in CH_3OH is added, and the solution is evaporated to dryness in vacuo leaving $(\text{NF}_2)_3\text{CN}(\text{CH}_3)\text{CH}_2\text{COO}^- \text{Mg}^{++}$ as a solid which can be purified as described in Example 1.

EXAMPLE 12

Preparation of

by the following reactions:

Perfluoroguanidine and $\text{HN}=\text{CHCH}_2\text{CH}_2\text{CN}$ are reacted and fluorinated according to the procedure of Example 11 to form $(\text{F}_2\text{N})_3\text{C}-\text{N}=\text{CHCH}_2\text{CH}_2\text{CN}$. This nitrile is heated with an equimolar quantity of $\text{H}_2\text{NCH}_2\text{CH}_2\text{NH}_2$ in ethanol and a two molar equivalent of acetic acid is added until the cooled solution is neutral. The solvent is removed in vacuo and

is obtained.

EXAMPLE 13

Following the procedure of Example 5, the adduct $\text{CH}_3\text{OCOCH}_2\text{OC}(\text{NF}_2)_2\text{NFH}$ is prepared in about 90% conversion from 63 mg. of dry methyl glycolate, 120 mg. of perfluoroguanidine in 0.2 ml. dry acetonitrile as solvent. The F n.m.r. absorptions are at -21.6ϕ (due to NF_2) and $+140.7 \phi$ (double quintuplet due to NFH).

The adduct is fluorinated to yield $\text{CH}_3\text{OCOCH}_2\text{OC}(\text{NF}_2)_3$ (single absorption in F n.m.r. at -23.4ϕ due to NF_2). The fluorination is carried out essentially quantitatively by continuously recirculating 3.5% F_2 (2 equivalents, based on the reaction $-\text{NFH} + \text{F}_2 \rightarrow -\text{NF}_2 + \text{HF}$) diluted with N_2 through a solution of the adduct in trifluoroethanol. The reaction time is 19 hours (3 hours between -23° and 20°C ; 16 hours at 20°C).

The $\text{CH}_3\text{OCOCH}_2\text{OC}(\text{NF}_2)_3$ compound is purified by gas liquid chromatography at 80°C . employing polydimethylsiloxane on diatomaceous earth.

The $\text{CH}_3\text{OCOCH}_2\text{OC}(\text{NF}_2)_3$ product is saponified using the procedure of Example 5 to yield $\text{Li}^+\text{O}^- \text{COCH}_2\text{OC}(\text{NF}_2)_3$.

EXAMPLE 14

Preparation of $[(\text{F}_2\text{N})_3\text{COCH}_2\text{CONH}(\text{CH}_2)_6\text{N}^+(\text{CH}_3)_3\text{PO}_4]^-$ and $(\text{F}_2\text{N})_3\text{COCH}_2\text{CO}_2(\text{CH}_2)_4\text{N}^+(\text{CH}_3)_3\text{Br}^-$ by the following reactions:

A mixture of equimolar amounts of $\text{CH}_3\text{OCOCH}_2\text{OC}(\text{NF}_2)_3$, prepared as described in Example 13, and $\text{H}_2\text{N}(\text{CH}_2)_6\text{N}^+(\text{CH}_3)_3\text{HCl}^-$ are heated in ethanol. The solution is evaporated to dryness and the semi-solid residue is mixed with a one third molar amount of 50 percent phosphoric acid solution. This mixture is evaporated to dryness with stirring in vacuo and the product,

19

$[(F_2N)_3COCH_2CONH(CH_2)_6N^+(CH_3)_3H]_3PO_4^{-3}$, is obtained.

A mixture of equimolar amounts of $CH_3OCOCH_2OC(NF_2)_3$ and $HO(CH_2)_4N^+(CH_3)_3Br^-$ in acetonitrile is heated with stirring. The solvent is removed in vacuo leaving a semi-solid residue of $(F_2N)_3COCH_2CO_2(CH_2)_4N^+(CH_3)_3Br^-$.

EXAMPLE 15

Preparation of

15

An equimolar mixture of $CF_3CF=N$ F and $HO(CH_2)_4CN$ is reacted at 0°C. in dimethyl ether in a closed glass pressure vessel. The product is separated and fluorinated according to the procedures of Example 11 and $CF_3C(NF_2)FO(CH_2)_4C = N$ is thus obtained. This nitrile is dissolved in anhydrous ethanol and anhydrous gaseous hydrochloric acid is slowly introduced until 2 molar equivalents are introduced. The compound,

30

is present. Two molar equivalents of anhydrous ammonia in dry ethanol is added and after two hours the solution is decanted. The compound

40

is present. An equimolar amount of picric acid is added and the solvent is removed in vacuo leaving the compound,

50

as a yellow semi-solid.

EXAMPLE 16

Preparation of $(F_2N)_3COCH_2C = C^-Li^+$ by the following reactions:

60

20

An equimolar amount of propargyl alcohol and perfluoroguanidine is reacted and fluorinated according to the procedure of Example 7. The compound, $(F_2N)_3COCH_2C = CH$, thus obtained is dissolved in dry benzene and an equimolar amount of butyl lithium in heptane is slowly added. The compound, $(F_2N)_3COCH_2C = C^-Li^+$, is obtained as a white solid.

EXAMPLE 17

Preparation of

by the following reactions:

The compound, $HO_2CCH_2OC(NF_2)_2NFH$, is obtained as described in Example 5. To the acetonitrile solution containing this compound is added two molar equivalents of triethylamine with stirring at about -20°C. The solvent is removed in vacuo leaving a residue which contains

40

This compound is also obtained when a 10 mole equivalent of sodium fluoride powder is added to the solution containing $HO_2CCH_2OC(NF_2)NFH$ and the solution is heated at 60°C. for 2 hours. The solution is filtered to remove sodium fluoride and to the filtrate is added an equimolar amount of triethylamine in acetonitrile. The compound,

50

is obtained as a solid residue.

EXAMPLE 18

According to the procedures of Example 8, ethanolamine perchlorate is reacted with the following fluorimino compounds and the resulting adducts are fluorinated to form the products indicated.

Addend compound	Fluorinating compound	-NFH containing adduct salts	Unsaturated adduct salts	Fluorinated adduct salts
$\text{HOCH}_2\text{CH}_2\text{NH}_2\text{ClO}_4^-$	$\text{C}_3\text{F}_7\text{CF}=\text{NF}$	NF^- $\text{C}_3\text{F}_7\text{COCH}_2\text{CH}_2\text{NH}_2\text{ClO}_4^-$	$\text{C}_3\text{F}_7\text{COCH}_2\text{CH}_2\text{NH}_2^+$ $\text{C}_3\text{F}_7\text{CF}=\text{OCH}_2\text{CH}_2\text{NH}_2^+$ $\text{C}_3\text{F}_7\text{CF}=\text{OCH}_2\text{CH}_2\text{NH}_2\text{ClO}_4^-$	NF_2^- $\text{C}_3\text{F}_7\text{CF}=\text{OCH}_2\text{CH}_2\text{NH}_2^+$ $\text{C}_3\text{F}_7\text{CF}=\text{OCH}_2\text{CH}_2\text{NH}_2\text{ClO}_4^-$

EXAMPLE 19

Preparation of the mixed salt, $(\text{F}_2\text{N})_3\text{COCH}_2\text{CO}_2^- \text{H}_3\text{N}^+ \text{CH}_2\text{CH}_2\text{OC}(\text{NF}_2)_3$, by the following procedure:

The acid, $(\text{F}_2\text{N})_3\text{COCH}_2\text{CO}_2\text{H}$, prepared as described in Example 5 and the amine, $\text{H}_2\text{NCH}_2\text{CH}_2\text{OC}(\text{NF}_2)_3$, prepared as described in Example 8, are each dissolved in dry acetonitrile and the solutions are mixed at 25°C. The solvent is removed in vacuo at 25°C, leaving the pure salt, $(\text{F}_2\text{N})_3\text{COCH}_2\text{CO}_2^- \text{H}_3\text{N}^+ \text{CH}_2\text{CH}_2\text{OC}(\text{NF}_2)_3$.

EXAMPLE 20

According to the procedures of Example 19, the following salts are prepared from compounds prepared in Examples 1-19.

20	Reactants	Ionic Product
	$(\text{F}_2\text{N})_3\text{COCH}_2\text{CO}_2\text{H}$ (Ex. 5) and $(\text{F}_2\text{N})_3\text{CON}=\text{CHCONHNH}_2$ (Ex. 2)	$(\text{F}_2\text{N})_3\text{COCH}_2\text{CO}_2^- \text{NH}_3^+ \text{NH}-\text{COCH}=\text{NOC}(\text{NF}_2)_3$
	$(\text{F}_2\text{N})_3\text{COCH}_2\text{CO}_2\text{H}$ (Ex. 1) and $(\text{F}_2\text{N})_3\text{CON}=\text{CHCONHNH}_2$ (Ex. 2)	$(\text{F}_2\text{N})_3\text{COCH}_2\text{CO}_2^- \text{NH}_3^+ \text{NH}-\text{COCH}=\text{NOC}(\text{NF}_2)_3$
25	$(\text{F}_2\text{N})_3\text{CON}=\text{CHCONHNH}_2$ (Ex. 2)	$(\text{F}_2\text{N})_3\text{COCH}_2\text{CO}_2^- \text{NH}_3^+ \text{NH}-\text{COCH}=\text{NOC}(\text{NF}_2)_3$
	$(\text{F}_2\text{N})_3\text{CON}=\text{CHCO}_2\text{H}$ (Ex. 1) and $(\text{F}_2\text{N})_3\text{COCH}_2\text{CH}_2\text{NH}_2$ (Ex. 8)	$(\text{F}_2\text{N})_3\text{COCH}_2\text{CO}_2^- \text{N}^+ \text{H}_3\text{CH}_2\text{CH}_2\text{OC}(\text{NF}_2)_3$

EXAMPLE 21

To a mixture of 0.28 g. (1×10^{-3} mole) of 2,4,6-tricarbomethoxybenzyl alcohol in 0.3 ml. of acetonitrile is added 0.15 g. (1×10^{-3} mole) perfluoroguanidine at -111°C . The mixture is allowed to react in a closed tube at 25°C . overnight. The solvent is then removed under vacuum and 1 ml. of trifluoroethanol is added to the liquid residue. Fluorination is accomplished using the procedure of Example 1 using 2×10^{-3} mole of fluorine diluted to about 5 percent with nitrogen. The fluorinated adduct is converted to the sodium salt by heating the trifluoroethanol solution with about 40 mg. of sodium hydroxide dissolved in 0.3 cc. of water for 30 minutes at 60°C . The salt is isolated by evaporation of the solvent under vacuum. Alternatively the neat fluorinated adduct may be treated with 34 mg. of 95 percent hydrazine (a solvent such as acetonitrile may be used). The temperature is maintained below 25°C . by cooling in an ice-bath. At the end of 1 hour the solvent, if any, is removed under vacuum and the residue is dissolved in one ml. of water containing 100 mg. of perchloric acid at 25°C . After about 30 minutes water is removed by vacuum. The resulting perchlorate salt may be purified by recrystallization, solvent extraction or other suitable means.

EXAMPLE 22

To a solution of 0.16 g. (1×10^{-3} mole) of the oxime of methyl mesoxalate in 0.3 ml. of acetonitrile is added 0.15 g. (1×10^{-3} mole) perfluoroguanidine at -110°C . The mixture is allowed to react in a closed tube at 25°C . overnight. The solvent is removed under vacuum, 1 ml. trifluoroethanol added to the residual liquid adduct, and the adduct fluorinated following the procedure of Example 1 using 3×10^{-3} mole of fluorine diluted to about 5 percent with nitrogen and employing a sodium fluoride scrubber to remove hydrogen fluoride from the recirculating gas stream.

The fluorinated adduct, $(\text{F}_2\text{N})_3\text{CON}=\text{C}(\text{COOCH}_3)_2$, is converted to the lithium salt by heating the trifluoroethanol solution with 50 mg. of lithium hydroxide dissolved in 0.3 cc. of water for about 1 hr. at 60°C . The salt is isolated by evaporation of the solvent under vacuum.

EXAMPLE 23

Preparation of

by the following reactions:

To a mixture of 0.17 g. glutaric acid (1×10^{-3} mole), 0.003 g. of urea, and 0.2 ml. of acetonitrile is added 0.149 g. perfluoroguanidine (1×10^{-3} mole). The resulting adduct is fluorinated according to the procedure of Example 1 with a three-fold excess of fluorine at 0°C . The sodium salt, $\text{Na}^+\text{O}^-\text{C}(\text{CH}_2)_3\text{CO}_2\text{C}(\text{NF}_2)_3$, is prepared by neutralization of the resulting fluorination mixture with dilute sodium hydroxide solution.

What is claimed is:

1. A compound of the formula:

25

30

wherein the expression inside the outer brackets represents a first ion and Z represents a second ion of opposite charge from the first ion, and

35

A is selected from the class consisting of fluorine and difluoramino groups,

E is selected from the class consisting of fluorine, difluoramino, perfluoroalkyl, difluoramino-substituted perfluoroalkyl, difluoramino-substituted perfluoroalkylfluoramino and

40

groups,

45

D is selected from the class consisting of $-\text{NF}_2$, $-\text{NFH}$ and $=\text{NF}$,

Y is selected from the class consisting of $-\text{O}-$, $-\text{N}=\text{CH}-$, $-\text{O}-\text{N}=\text{CH}-$,

and $-\text{NX}-$,

X is selected from the class consisting of hydrogen and alkyl groups containing not more than six carbon atoms,

R is selected from the class consisting of mono-, di- and tri-covalent ionic charge bearing groups,

a and b each have values from 1 to 3,

m and n are the ionic charges of the individual first and second ions and have integer values from -3 to +3,

p is the covalence of R ,

r is the covalence of E and

q is 0-1;

provided that ma equals $-nb$, that when r is 2, p is 1 and that when D is $=\text{NF}$, q is 0.

2. A compound according to claim 1 wherein Z is the anion.
3. A compound according to claim 1 wherein Z is a mono-valent anion.
4. A compound according to claim 1 wherein Z is a 5 divalent anion.
5. A compound according to claim 1 wherein Z is a tri-valent anion.
6. A compound according to claim 1 wherein Z is a monovalent cation.
7. A compound according to claim 1 wherein Z is a divalent cation.
8. A compound according to claim 1 wherein Z is a trivalent cation.
9. A compound according to claim 1 wherein the expression inside the outer brackets is a monovalent anion.
10. A compound according to claim 1 wherein the expression inside the outer brackets is a divalent anion.
11. A compound according to claim 1 wherein the 20 ClO_4^- expression inside the outer brackets is a trivalent anion.

12. A compound according to claim 1 wherein the expression inside the outer brackets is a monovalent cation.
13. A compound according to claim 1 wherein the expression inside the outer brackets is a divalent cation.
14. A compound according to claim 1 wherein the expression inside the outer brackets is a trivalent cation.
15. A compound according to claim 1 which contains 50 to 70 weight per cent of fluorine bonded to nitrogen and of oxygen.
16. A compound according to claim 1 wherein Z is selected from the class consisting of ClO_4^- NO_3^- ClO_3^- BrO_3^- IO_3^- , Li^+ , Na^+ , K^+ , NH_4^+ , NH_2NH_3^+ , Mg^{++} and Be^{++} .
17. A compound according to claim 1 wherein Z falls within the definition of the first ion thereof.
18. A compound according to claim 16 wherein Z is
